UNITED STATES PATENT OFFICE.

STEPHEN BILEK, OF CHICAGO, ILLINOIS.

DESIGN FOR A PICTURE-FRAME.

No. 38,510.

Specification for Design.

Patented April 2, 1907.

Application filed February 20, 1907. Serial No. 358,509. Term of patent 3½ years.

To all whom it may concern:

Be it known that I, STEPHEN BILEK, a citizen of the United States, residing at Chicago, in the county of Cook and State of Illinois, have invented a new, original, and ornamental Design for Picture-Frames, of which the following is a specification, reference being had to the accompanying drawing, forming part thereof.

The figure is a plan view of a picture-frame, showing my new design.

I claim—

The ornamental design for the picture-frame as shown.

STEPHEN BILEK
